[57] CLAIM

The ornamental design for a golf tee and ball setting device, as shown and described.

DESCRIPTION

FIG. 1 is a front, top and side perspective view of a golf tee and ball setting device showing our new design, the broken lines illustrating a golf tee positioned in said device are for illustrative purposes and form no part of the claimed design; FIG. 2 is a top plan view;

FIG. 3 is a left side elevational view;

FIG. 4 is a front elevational view, the rear the rear being a mirror image thereof, and the broken lines illustrating a golf tee and ball positioned in the device are for illustrative purposes only and form no part of the claimed design;

FIG. 5 is a bottom plan view; and,

FIG. 6 is an elevational view of the right side.
